UNITED STATES PATENT OFFICE

125,445

DESIGN FOR A COMPASS

Walter E. Hull, Warren, Ohio

Application July 25, 1940, Serial No. 93,923

Term of patent 14 years

To all whom it may concern:

Be it known that I, Walter E. Hull, a citizen of the United States, residing at Warren, in the county of Trumbull and State of Ohio, have invented a new, original, and ornamental Design for Compasses, of which the following is a specification, reference being had to the accompanying drawing, forming part thereof.

Figure 1 is a perspective view taken from the side of a compass, showing my new design; and Figure 2 is a perspective view taken from the end of the compass shown in Figure 1.

I claim:

The ornamental design for a compass, as shown.

WALTER E. HULL.
